Primary Examiner — Cynthia Ramirez*(74) Attorney, Agent, or Firm* — Richard M. Goldberg(57) **CLAIM**

The ornamental design for a three bin multi-sort central recycling station, as shown and described.

DESCRIPTION

FIG. 1 is an isometric view of the three bin multi-sort central recycling station of my design, viewed from the top and front, with the flaps in a closed configuration;

FIG. 2 is an isometric view thereof, viewed from the top and front, with the flaps in an open configuration;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
